UNITED STATES PATENT OFFICE

2,299,986

DOOR OPENER

Arthur F. Hummel, Sligo, Pa.

Application March 20, 1941, Serial No. 384,399

2 Claims. (Cl. 268—35)

This invention relates to a door opener, the invention being mainly designed for garage doors, the general object of the invention being to provide means for opening the doors when a car approaches a garage and means for closing the doors after the car enters the garage and such doors being again opened when the car starts to leave the garage and the doors closing after the car has left the garage.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a top plan view of the invention.

Figure 2 is a side view with parts in section.

Figure 3 is a top plan view with the garage in horizontal section.

Figure 4 is a section on the line 4—4 of Figure 3.

Figure 5 is a section on the line 5—5 of Figure 4.

Figure 6 is a diagrammatic view of the operating means for the door.

Figure 7 is a section on the line 7—7 of Figure 6.

Figure 8 is a section on the line 8—8 of Figure 7.

Figure 9 is a detail view showing the clutch arrangement for moving the arms from a shaft which controls door opening means.

Figure 10 is a detail view showing the shaft and the arms for the device within the garage and operated by the front wheels of a vehicle.

Figure 11 is a view of the levers forming part of the door operating means.

In these drawings the letter A indicates a building which is shown as a garage and the letters D indicate the doors thereof, these doors being normally held closed by the springs B which can have their tension adjusted by placing their front ends in any suitable ones of a plurality of holes 1 formed in the brackets 2 connected to the inner faces of the doors. A shaft 3 is suitably supported within the garage and an arm 4 is carried by the shaft and a link 5 connects this arm with one of the other doors and this link is adjustably connected with the door by having one end engaging in one of the holes 1 of the bracket 2 of said door. A second arm 6 is carried by the shaft 3 and a link 7 connects this arm 6 with the bracket 2 of the door so that this link can be adjustably connected with the said other door. Projections 8 are connected with the inner ends of the arms

4 and 6, see Figure 11, so that movement of the arm 4 will be communicated to the arm 6 in an opening movement of the arm 4 so that both doors will be opened when the arm 4 is moved in an anti-clockwise direction in Figure 11. However, arm 6 can be moved without moving the arm 4 when the other door is open, thus permitting the other door to be opened without opening the door to which the arm 4 is connected. A vertically arranged shaft 9 is supported for rotary movement in the garage and has an arm 10 at its upper end which is connected by a link 11 with said bracket 2 to which the arm 4 is connected so that when the shaft 9 is rotated in a certain direction it will open the door to which the arm 4 is connected and movement of this door will move the arm 4 and cause movement of the arm 6 so that the other door will be open and thus both doors will be open simultaneously though as before stated the second door can be opened by hand whenever desired.

The shaft 9 extends into a housing 12 preferably located below the floor of the garage and said shaft has attached thereto the clutch part 13 and the clutch part 14. An arm 15 is rotatably arranged on the shaft 9 within the housing and has a clutch part 16 thereon for cooperating with the clutch part 13 when the arm 15 is moved in one direction. This arm 15 is connected by the flexible means or rods 17, which include the spring means 18, with an arm 19 having a clutch part 20 rotatably arranged on a shaft 21 supported for rotary movement in a housing 22 embedded in the roadway leading to the garage. An inverted U-shaped member 23 has the lower ends of its limbs connected with the shaft 21 and said limbs pass through slots 24 formed in the cover 25 of the housing 22 with the bight located a distance above the housing and adapted to be struck by the wheels of a vehicle approaching or leaving the garage. A clutch part 26 is fastened to the shaft 21 and cooperates with the clutch part 20 of arm 19 to move the arm 19 when the member 23 is rocked toward the garage by a car moving toward the garage. A spring 27 connects a part of the shaft 21 with the bottom of the housing 22 and acts to hold the parts with the member 23 in active position. The member 23 is held in lowered position after being lowered by a car striking the same with the car approaching the garage, by a latch member 27 engaging a pin 28 on one of the limbs of the member 23. The cover member is formed with the grooves 25' for receiving the bight of the member 23 when the member 23 is in lowered position.

A second housing 30 is embedded in the floor of the garage or other floor and has a shaft 31 journaled therein to which is connected the lower end of an inverted U-shaped member 32 which passes through slots in the cover member or the garage floor so that its bight can be engaged by the front wheels of a vehicle after the vehicle has entered the garage. An arm 33 depends from the shaft and is rotatably mounted thereon and has a clutch projection 34 thereon for engaging a clutch collar 35 fastened to the shaft 31. Rods or the like 36 connected together by a spring 37 connect the arm 33 with an arm 38 the hub of which has a segmental part 40 and said hub is pivoted to a shaft 41 in the housing 12, see Figure 5, and the toothed part 40 is adapted to mesh with a toothed portion of a disk 42 on shaft 9 and having a clutch part for engaging the clutch part of collar 14. Thus when the collar 42 is rotated by movement of the arm 38 the shaft 9 will be moved to open the door.

A wire 45 or the like extends from a part on shaft 21 in housing 22 to the latch member 46 in housing 38, this latch member 46 acting to hold the member 32 in depressed position and a wire 47 or the like extends from a part of the shaft 31 in housing 30 to the latch member 27 in the housing 22.

Thus it will be seen that a car approaching the garage will strike the member 23 and push the same over in the direction toward the garage and said member will be held in lowered position by the latch 27. This movement of the member 23 will cause the connection 17 to pull upon the arm 15, the clutch part 16 of which will impart a rotary movement to the collar 13 so that the shaft 9 is partly rotated and in turn causes the arm 19 to operate the door opening means so as to open the doors. The fact that the member 23 is held in lowered position by the latch 27 will hold the doors in open position. The car then passes into the garage through the open doors until its front wheels run over the member 32 of the housing 30. This action will not exert a pull upon the connection 36 to operate the arm 38 due to the clutch parts 34 and 35 but this movement of the member 32 will cause a pull upon the connection 47 which releases the latch 27 so that the member 23 in housing 22 can rise and thus the parts are released so that the springs B can close the doors. The front wheel passes entirely over the member 32 so that said member 32 can rise in rear of the front wheel and then when the car is backed to remove it from the garage it will strike the member 32 and move the same toward the doors of the garage and this will cause rotary movement of the clutch parts 31 and 35 which results in a movement of the arm 33 to exert a pull upon the connection 36 which, in turn, causes the arm 38 through the connections 40, 42 and 14 to rotate the shaft 9 to open the doors and the member 32 is held in lowered position by the latch member 46 which is similar to the latch member 27. Thus the doors remain open so that the car can be backed from the garage. As the car passes over the member 23 said member is moved in a clockwise direction so that the clutch parts 20 and 26 will not move the arm 19 but this movement of the member 23 will, through the wire 45, exert a pull upon the latch means 46 so as to release the same to permit the member 32 to rise and the door springs to close the doors.

Thus it will be seen that I have provided simple means whereby the doors are automatically opened upon a car approaching the same and 75

then the doors are closed when the car enters the garage, with means for opening the doors when the vehicle starts to leave the garage and then closes the doors after the vehicle has left the garage.

5 A stop pin 59 is provided for each of the latch members 27 and 46 in the casings 22 and 30, this pin holding the latch member in position to receive the keeper pin 28 of either of the members 23 or 32. A coil spring 51 is arranged on the operating member 47 or 45 of the latch member and tends to hold the latch member against the pin 59. This spring prevents the latch member from moving too far in the direction of the pull of the member 45 or 47.

10 It is thought from the foregoing description that the advantages and novel features of the invention will be readily apparent.

15 It is to be understood that changes may be made in the construction and in the combination and arrangement of the several parts provided that such changes fall within the scope of the appended claims.

20 Having described the invention, what is claimed as new is:

25 1. In combination with a garage and its doors, spring means for closing the doors, means for opening one door by opening movement of the second door, a shaft in the building, means for opening the second door by movement in one direction of said shaft, a rockable member in front of the building, a shaft to which the rockable member is fastened, an arm depending from the shaft, clutch means for moving the arm when the rockable member is moved toward the building and leaving the arm free when the rockable member is moved away from the building, an arm on the door opening shaft, means for connecting the two arms together, clutch means for causing movement of the door opening shaft by the arm on the shaft, latch means for holding the rockable member in lowered position when the same is moved toward the building, a rockable member in the building, a shaft to which the rockable member is connected, an arm depending from the last-mentioned shaft, clutch means for connecting the arm with the last-mentioned shaft and for moving the arm when the rockable member is moved away from the doors, an arm pivoted in the building, a connection between said arm and the last-mentioned arm, means for moving the door operating shaft when the pivoted arm is moved, latch means for holding the second rockable member in lowered position, means for releasing the latch means when the first rockable member is moved away from the doors.

30 2. In combination with a building and its door, means for normally holding the door in closed position, a shaft in the building, means for opening the door by movement in one direction of said shaft, a rockable member in front of the building, a shaft to which the rockable member is fastened, an arm depending from the last-mentioned shaft, clutch means for moving the arm when the rockable member is moved toward the building and leaving the arm free when the rockable member is moved away from the building, an arm on the door opening shaft, means for connecting the two arms together, clutch means for causing movement of the door opening shaft by the arm on said shaft, latch means for holding the rockable member in lowered position when the same is moved toward the building, a rockable member in the building, a shaft

to which the rockable member is connected, an arm depending from the last-mentioned shaft, clutch means for connecting the last-mentioned arm with the last-mentioned shaft and for moving the arm when the rockable member is moved away from the door, an arm pivoted in the building, a connection between said arm and the last-

mentioned arm, means for moving the door operating shaft when the pivoted arm is moved, latch means for holding the second rockable member in lowered position, means for releasing the latch means when the first rockable member is moved away from the door.

ARTHUR F. HUMMEL.
